UNITED STATES PATENT OFFICE.

CHARLES WILLIAM ORVIS, OF WESTPLAINS, MISSOURI.

VISE.

SPECIFICATION forming part of Letters Patent No. 727,679, dated May 12, 1903.

Application filed January 8, 1903. Serial No. 138,232. (No model.)

To all whom it may concern:

Be it known that I, CHARLES WILLIAM ORVIS, a citizen of the United States, residing at Westplains, in the county of Howell and 5 State of Missouri, have invented certain new and useful Improvements in Vises; and I do hereby declare the following to be a full, clear, and exact description of the invention, such as will enable others skilled in the art to which 10 it appertains to make and use the same, reference being had to the accompanying drawings, and to the figures of reference marked thereon, which form a part of this specification.

This invention comprises a vise having parallel jaws, one of which slides to and from the other under the power of a lever acting, by means of a vertically-sliding block, upon inclined planes formed in the jaws, giving a wedge action to close and open the jaws. 15 The object of the invention is to form an improved device of the kind stated in which, among other advantages, the jaws may be adjusted to take and hold stuff of different sizes. 20

25 In the accompanying drawings, Figure 1 is a front elevation, Fig. 2 is a side elevation, and Fig. 3 is a plan view, of the several parts of the device separated.

Referring specifically to the drawings, the 30 fixed jaw of the vise is indicated at 1 and the movable jaw at 2. The latter is parallel to the former and retains its parallelism during its movements. It slides to and from the fixed jaw on guide-arms 2^a, which project 35 from the fixed jaw and work in ways 2^b, formed in the sides of the movable jaw. The jaws have opposite longitudinal recesses, as indicated at 3, in which the block 7 slides vertically when operated by the lever 6, which 40 is conveniently located as a foot-lever. At each side of each recess are upper and lower inclined ribs 8. These ribs incline downwardly and outwardly from the meeting faces of the jaws, and the upper and lower ribs on 45 each side of the recess and in each jaw project into notches 4^a, formed in upper and lower cross-pieces 4, carried by the block 7. The notches are properly inclined to receive the ribs, and in the reciprocation of the block 50 the notches engage and slide along the ribs. This produces a wedge action, which moves the movable jaw at both top and bottom and either closes or opens the jaws, according to downward or upward movement of the lever.

To afford an adjustable fulcrum for the 55 lever, a fulcrum-block 5 is attached to the fixed jaw and has a notched slot, as indicated at 5^a, into any of which notches the end of the lever may be put, which action is permitted by the swinging link 6^a, connecting the 60 lever and the block 7. The vertically-adjustable fulcrum allows the jaws to be set at various distances apart, so as to be adaptable to objects of different sizes, and the parallel movement of the jaws makes the vise 65 particularly effective for holding squared stuff, such as boards or timbers, which with pivoted-jaw vises are pinched at one edge only. The wedge action above indicated makes a quick movement, quicker than a 70 screw. When in use, the device may, if necessary, be held closed by foot-pressure on the lever. The purpose of having upper and lower cross-pieces 4 and consequent upper and lower wedge engagement is to make the 75 movement equal at both top and bottom of the movable jaw, thereby maintaining parallelism and preventing pinching or binding on the guide-arms.

What I claim as new, and desire to secure 80 by Letters Patent, is—

1. In a vise, the combination with jaws having opposite longitudinal recesses and inclined ribs beside the recesses, of a wedge-block sliding vertically in the recesses and 85 having notches receiving the ribs, and an operating-lever connected to the block.

2. In a vise, the combination with a fixed jaw, of a movable jaw parallel thereto, a vertically-slidable wedge-block having upper 90 and lower engagement with the jaws, so as to maintain the parallelism, and means to operate the wedge-block.

3. In a vise, the combination with fixed and movable parallel jaws having opposite 95 longitudinal recesses and upper and lower inclined ribs projecting into the recesses, of a block slidable vertically in the recesses and engaging the ribs, and an operating-lever connected to the block.

100 In testimony whereof I affix my signature in presence of two witnesses.

CHARLES WILLIAM ORVIS.
